UNITED STATES PATENT OFFICE.

HENRY F. BARBER, OF FORT MORGAN, COLORADO, ASSIGNOR OF
SEVEN-TWELFTHS TO JOHN G. JONES AND FRANK M. TEFFT, OF
FORT MORGAN, COLORADO.

BEET-HARVESTER.

SPECIFICATION forming part of Letters Patent No. 784,532, dated March 14, 1905.

Application filed April 9, 1904. Serial No. 202,418.

To all whom it may concern:

Be it known that I, HENRY F. BARBER, a citizen of the United States, residing at Fort Morgan, in the county of Morgan and State of Colorado, have invented new and useful Improvements in Beet-Harvesters, of which the following is a specification.

My invention relates to improvements in what may be designated as "beet-harvesters." It has for its object to provide for the effective excavating or removal from the ground of the beets and the elevating thereof for "topping" and finally delivering the same for transference to a suitable place of storage, to accommodate the passage of beets of varying sizes, to means feeding them to the cutting or topping contrivance, to suitably effect the adjusting of the beet-feed-controlling means according to the feeding action it may be desired to impart to the beets as in passing them to the topping or severing means and for delivery, and to otherwise provide for convenience and facility in carrying out the aforesaid purposes.

Said invention consists of certain structural features and the combination and arrangement of parts substantially as hereinafter more fully disclosed, and specifically pointed out by the claims.

In the accompanying drawings, illustrating the preferred embodiment of my invention, Figures 1 and 2 are respective side elevations of the latter. Fig. 3 is a broken plan view thereof. Fig. 4 is a vertical cross-section produced in rear of and viewing the offbearing conveyor or carrier taking the beets from the primary or initial carrier or elevator. Fig. 5 is a rear elevation, and Fig. 6 is a longitudinal section, of the machine. Fig. 7 is a detailed view showing more especially the upper portion of the primary carrier or elevator and adjunctive parts with portions broken away. Fig. 8 is a like view of the beet-controlling device. Fig. 9 is also a like view of the spring-guard opposed to the beet-offbearing apron or carrier. Fig. 10 is a detached view of the combined plow-beam-guiding standard and forward-axle linchpin.

In the practicing of my invention I arrange

generally all of the various parts thereof in or upon a suitably-constructed frame 1, itself 50 mounted upon a rear axle 2, bearing-wheels 3, and upon a forward swiveled axle 4, having wheels 5 and a draft bar or pole 6.

An elevator or carrier 7 of suitable slatted-belt construction is arranged and supported 55 between upward and rearward inclined lateral bars or members 7^a, having passing therethrough at their extreme upper ends and some distance therebelow a shaft 8 and a rod or shaft 9, respectively, said shaft 8 bearing in 60 an arm 10 and a supplemental frame 10^a. An additional shorter like carrier 11 is arranged laterally of the carrier or elevator 7 at its upper end and encompasses rolls 11^a, secured upon the shafts 8 and 9^a, serving to aid the elevation and spreading of the beets when at that altitude to more effectively deliver them to and distribute them upon the carrier subsequently receiving them, as presently described. To the lower ends of the elevator lateral bars 7^a 70 are suitably secured by their rear ends parallel excavators or plows 12, adapted to lift the beets out of the ground, said plows or excavators being equipped with upward and rearward inclined convergent arms 12^a, with 75 their upper ends juxtaposed to the lower end of the carrier or elevator 7 to aid in guiding the beets lifted or removed by said plows upon said carrier or elevator. Said elevator lateral bars have secured laterally thereto the 80 rear ends of the divergent arms of a beam 13, having its forward end portion extending through the elongated vertical guide-slot 13^a of the linchpin 14, effecting the swiveled or turning connection between the forward end 85 of the frame 1 and the axle of the forward wheels. Said linchpin or standard has apertures 14^a therethrough to permit the inserting thereinto a pin for the retention of the plow-beam in an elevated position out of contact 90 with the ground or surface, as when the machine is not in use. To said plow-beam is linked, as at 15, a rock-bar or yoke 16, bearing in the lateral bars of the frame 1, and to said yoke is secured or fixed the inner end of 95 a hand-lever 17 for effecting the requisite or

desired adjustment of the plow-beam, as in causing the plow to penetrate the soil to a greater or less depth, the purpose of which is obvious. Said lever has, as usual, a sliding 5 detent or pawl 17^a, engaging a rack 17^b, fixed to the frame 1, for the retention of said lever at the desired point of adjustment, said detent being actuated by the hand of the operator sitting in the seat 18, supported upon 10 the frame 1, and grasping said lever and a supplemental lever 17^c, pivoted to the latter and linked, as at 17^d, to said detent. The elevator or carrier 7 and supplemental carrier or belt 11 have the common shaft 8 of their pulleys provided with a driving sprocket wheel or pinion 19 for effecting the movement thereof, as will be presently disclosed.

Disposed adjacently to the upper or delivering ends of the carriers 7 and 11 is a carrier or 15 conveyer 20 with its carrying-surface presented next to the latter and arranged at right angles to the plane of the aforesaid carriers and encompassing upright rolls or pulleys 20^a, with their shafts suitably supported in position, one of which shafts, however, is adapted to carry with it one of said pulleys or rolls as it is rotated or driven by a pinion 21, secured to said shaft and engaging a large laterally-cogged wheel or pinion 22. Said wheel 20 or pinion 22, whose shaft 22^a is suitably supported in position, has fixed to it laterally a small sprocket wheel or pinion 22^b, again later referred to, for finally imparting motion to the carrier or conveyer 20, as will hereinafter 25 be described. Said carrier or conveyer has its delivering end extending a short distance beyond the frame 1 laterally, and to said frame just opposite said extension of said carrier is suitably connected, as further noted, 30 an upstanding deflector or plate 23 with its greater area or surface presented in a plane at right angles to the direction of the movement of said carrier and so arranged that a portion of said surface or area is adapted to 35 intercept the beets carried by the conveyer or carrier 20, and thus provide for the precipitating or throwing the same downward and inward upon means, as a deeply grooved or corrugated traveling carrier or conveyer 40 24, later further described, for the conducting of said beets to the knife or cutter for topping the same, as will be more fully apparent presently. Said deflector or plate has a lateral tubular or sleeve extension 23^a near 45 its bottom edge, slipped or inserted upon a bar extension or arm 23^b of the frame 1, and through said sleeve or tubular extension are coincident apertures 23^c, while said arm or bar extension has a number of apertures 23^d 50 to provide for the reception or insertion therethrough of a pin 23^e, as in effecting the lateral adjustment of said plate or deflector to provide for controlling the feeding or throwing of the beets upon the carrier 24.

65 A spring-metal plate 25, with one right-angled end portion suitably held in position in preferably a slotted standard 25^a, secured to the frame 1, say, directly opposite the plate or deflector 23, has its main portion or surface arranged in a plane parallel to the carrier or conveyer 20 to aid the latter in guiding or feeding the beets as aforesaid. The opposite right-angled end portion of said plate 25 is arranged close to the bracket-arm 10, before noted, and by its resilient or springy character 70 springs back and forth as said plate yields or flexes under the pressure or resistance of the contacting beets, thus providing for accommodating the passage therebetween and the carrier 20 of beets of different sizes, 75 as will be readily appreciated.

The carrier or conveyer 24, previously alluded to, is arranged just below the spring-plate guide 25 and the carrier or conveyer 20 and adjacently to the deflector 23 to receive 80 and carry in its deep channels or grooves the beets thrown, as above noted, thereto by said deflector and suitably encompasses opposite rolls 24^a, the shaft of one of which has secured thereon a sprocket-pinion 26 for actuating said shaft and carrier, said pinion itself being driven as presently seen, the other of said shafts carrying a large gear-wheel 27, the function of which will appear later.

A two-blade knife or cutter 28, carried by 90 a shaft 28^a, suitably journaled in position, and whose cutting edges face or are presented in opposite directions, is arranged laterally and close to one edge of the carrier 24, so that with the "tops" of the beets carried by and 100 extending laterally beyond the last named said tops will be brought into position to be severed from the beets by the action of said knife in rapid rotation, said rotation being effected by the action of a pinion 29, secured 105 to the shaft of said knife and geared to the wheel 27, secured to one of the shafts of the belt or carrier 20, driven as presently disclosed.

An elevator or conveyer 30 is also arranged 110 at the delivery or rear end of the machine and at right angles to the plane of the carrier 24 and so as to receive the topped beets therefrom and has its frame suitably supported in an upward and outward inclined position, its 115 upper end extending a suitable distance laterally beyond the machine-frame 1 to permit the delivery of the beets elevated thereby into a moving vehicle accompanying the machine or harvester, as will be readily understood, 120 for finally readily transferring said beets to a place of storage or otherwise conveniently disposing of the same. Said elevator has the shaft of its lower roll provided with a pinion 31, geared to a laterally cogged or toothed wheel 32, arranged upon the axle of the rear transporting-wheels of the harvester and suitably 125 driven for actuating said elevator. Upon one of said rear wheels is suitably carried a large cogged or gear wheel 33, having as its center, 130

and loosely inserted upon, the rear axle, and with said wheel is geared a pinion 34, fixed upon a shaft 34^a, suitably supported in position, said pinion carrying laterally a sprocket-pinion 35. A chain belt 36 engages said sprocket-pinion and the pinion 22^b of the actuating-gear of the carrier 20, the pinion 19 for driving the shaft upon which are secured the rolls imparting motion to the elevators 7 and 11 and the pinion 26 for actuating the shaft bearing the driving-roll for the carrier 24, whereby a common medial means is provided for actuating all of the aforesaid parts.

Latitude is allowed as to details herein, as they may be changed as circumstances suggest without departing from the spirit of my invention and the latter still be protected.

I claim—

1. In a machine of the character described, an elevator having its lateral bars equipped at their lower ends with excavating means, a transverse carrier arranged to receive the contents of said elevator and conduct the same laterally thereof, means adapted to deflect and precipitate said contents, a carrier to receive said precipitated contents, and a cutter arranged laterally of said latter carrier and adapted to engage said contents for the removal of the superfluous portion thereof.

2. In a harvester of the character described, an elevator equipped with excavating means, a transverse carrier arranged to receive the contents of said elevator and deliver it laterally thereof, and a spring-guide arranged parallel with said carrier and adapted to aid the action thereof.

3. In a harvester of the character described, an elevator equipped with excavating means, a transverse carrier receiving the contents of said elevator and delivering the same laterally thereof, a spring-guide opposed to and arranged to aid the action of, said carrier, a second carrier arranged in a plane below the aforesaid carrier, and a lateral deflector arranged to deliver said contents upon said second carrier.

4. In a harvester of the character described, an elevator equipped with excavating means, a transverse carrier with its carrying-surface

presented toward the upper delivery end of said elevator, a spring-guide opposed to said carrier, a laterally-arranged deflector adjustably disposed in position, a second carrier arranged in a plane below the aforesaid carrier and adapted to receive the objects precipitated by said deflector and a lateral cutter arranged to act upon the objects borne by said second carrier.

5. In a harvester of the character described, a transverse carrier, an elevator having excavating means delivering upon the aforesaid carrier, and a spring-guide with one right-angled end portion fixed in position and having its main portion arranged parallel to the carrying-surface of said transverse carrier, and its other right-angled end portion having frictional contact with a fixed part.

6. In a harvester of the character described, an elevator equipped with excavating means, a transverse carrier with its carrying-surface presented to the upper delivering end of said elevator, a deflector arranged laterally of said parts, a guide opposed to said transverse carrier, a second carrier arranged in a plane below the aforesaid carrier, shaft and gear-pinion mechanism, and a driving-belt common to the latter mechanism and adapted to transmit the action thereof to said elevator and carriers.

7. In a harvester of the character described, an elevator equipped with excavating means, a transverse carrier, with its carrying-surface presented toward the upper end of said elevator, means for aiding the action of said transverse carrier, a second carrier below the aforesaid carrier, a deflector for precipitating the objects carried by the first-referred-to carrier upon said latter carrier, means for "topping" said objects thus precipitated and received upon said latter carrier and a third carrier, adapted to receive said objects from said second carrier.

In testimony whereof I affix my signature in the presence of two witnesses.

HENRY F. BARBER.
